(57) **CLAIM**

We claim the ornamental design for an information handling system, as shown and described.

DESCRIPTION

FIG. 1 is a front perspective view of the information handling system in a closed position comprising the present invention;

FIG. 2 is a front view thereof in a closed position;

FIG. 3 is a rear view thereof in a closed position;

FIG. 4 is a right side view thereof in a closed position;

FIG. 5 is a left side view thereof in a closed position;

FIG. 6 is a top view thereof in a closed position;

FIG. 7 is a bottom view thereof in a closed position; and,

FIG. 8 is a front perspective view thereof in an open position.

Broken lines shown in the drawings illustrate portions of the information handling system, and form no part of the claimed design.
